COMB

August L. Voight, Berea, Ohio

Application May 3, 1947, Serial No. 745,748

5 Claims. (Cl. 132—24)

1

This invention relates to a new and improved comb and particularly to a comb used to form a roll of hair upon a woman's head.

An object of the invention is to provide a comb for forming a roll of hair upon a woman's head and which is efficient in use and easy to operate or apply.

Another object is to provide a comb as specified in the above object and which when applied is hidden from view by the roll of hair it forms.

A further object is to provide a comb as above referred to and which has improved and novel means for holding itself in applied position in the roll of hair.

A still further object is to provide a comb as above specified and which can be economically and efficiently manufactured from plastic or other suitable material.

Further and additional objects and advantages not hereinbefore referred to will become apparent during the detailed description which is to follow.

The invention contemplates a comb having a solid body strip portion from which extends a series of straight teeth while a series of curved or arcuate teeth extend from said body strip downwardly, laterally and upwardly. The series of curved teeth function to form a roll of hair upon the side of a woman's head or a roll of hair on the back of the head generally referred to as a chignon. The series of straight teeth function to retain the comb in the hair after the roll has been formed. The comb is so constructed that it will be entirely hidden from view when applied by the roll of hair in which the series of curved teeth are located and by the relatively straight hair in which the series of straight retaining teeth are located.

Referring to the accompanying drawing illustrating an embodiment of the invention,

Fig. 1 is an elevational view of one form of comb embodying the invention.

Fig. 2 is a top plan view of the comb shown in Fig. 1.

Fig. 3 is a diagrammatic illustration of the initial position of the comb in using it to form a roll of hair.

Figs. 4 and 5 are diagrammatic illustrations of two intermediate positions of the comb during its use to form a roll of hair, and

Fig. 6 is a diagrammatic illustration of the final position of the comb after the roll of hair has been formed and the comb completely applied to the head.

The comb comprises a solid body strip 10, which may be straight or curved depending upon

2

whether the roll to be formed by the comb is on the side or the back of the head. The comb illustrated, for purposes of explanation, is a curved comb and is suitable for forming a chignon upon a woman's head. Therefore the body strip 10 is curved from end to end and has depending therefrom a series of straight teeth 11 which are integral with the body strip while said series has from end to end the same curvature as the body strip. The series of straight teeth 11 may be designated as retaining teeth and, if desired, could be in the form of what is known in the art as "gripper" teeth. The body strip 10 also has integrally formed therewith a series of arcuate teeth 12 which extend downwardly from the strip 10, then laterally of the straight teeth 11 and then upwardly and inwardly toward the strip, with the free ends 13 of the arcuate teeth spaced from the strip 10 to provide a gap 14. The series of curved or arcuate teeth 12 from end to end have the same curvature as the strip 10 and the series of straight teeth 11. The curved or arcuate teeth 12 may be designated as forming teeth since they function to form the roll of hair.

The comb may be made economically and efficiently from suitable plastic material and preferably will have a certain measure of flexibility. The flexibility of the comb should be such that when it has the curved configuration from end to end as shown and described herein the ends of the comb can be slightly spread apart in applying the comb and then when released will grip the sides of the wearer's head and hold the comb in position around the back of the head.

The diagrammatic illustrations of Figs. 3 to 6 inclusive show the manner in which the comb is applied to the back of the wearer's head, it being understood that these views illustrate the hair at the back of the head.

In Fig. 3 the hair at the back of the head is shown as having been combed or brushed straight preparatory to applying the comb. The user of the comb then takes the same and spreads the ends thereof slightly apart and then positions it in the back of the head as indicated in Fig. 3, at which time the free ends 13 of the arcuate teeth 12 are slightly entering the hair while the straight teeth 11 are located in the hair near the ends thereof. The user then rotates the comb in the direction indicated by the arrow from its position of Fig. 3 into its position of Fig. 4. During such rotation the hair is partially formed into a roll with the curved teeth 12 entering farther into the hair. The user then continues the rotation of the comb in the direction indicated by the arrow from

the position of Fig. 4 into the position of Fig. 5, at which time the roll of hair is almost completed and the curved teeth 12 are substantially entirely within the nearly completed roll of hair, it being noted that a portion of the roll of hair has passed through the gap 14 and is located within the confines of the curved teeth 12.

It will also be noted by reference to Fig. 5 that at this time the straight teeth 11 are pointed angularly upwardly from the roll of hair. The user continues to rotate the comb in the direction of the arrow until the straight teeth 11 are pointing downwardly whereupon the comb is raised slightly and then moved downwardly into the position of Fig. 6. At this time the curved teeth 12 are completely located within the roll while the straight teeth 11 are located in the hair adjacent the roll.

It will be noted that the entire comb is concealed by the hair and that when the user releases the ends of the comb the latter will contract, due to the flexibility of the comb, and will grip the sides of the head. Thus the comb, together with the retaining function of the teeth 11, is maintained in position on the head.

From the foregoing it will be seen that a comb embodying the present invention can be readily and effectively applied to form a roll of hair and that when the roll has been formed the comb will be retained in position to maintain the roll and will be completely concealed.

Although a preferred embodiment of the invention has been illustrated and described it will be understood that the invention is susceptible of various modifications and adaptations within the scope of the appended claims.

Having thus described my invention, I claim:

1. A comb comprising a body strip, a series of straight teeth extending from said strip, and a series of arcuate teeth extending from said strip substantially laterally of said series of straight teeth, the convex sides of said arcuate teeth being disposed toward the free ends of said straight teeth.

2. A comb comprising a body strip, a series of straight teeth extending from said strip, and a series of arcuate teeth extending downwardly from, laterally and upwardly of and then toward said strip and having their free ends spaced from the upper edge of said strip to leave a predetermined gap therebetween.

3. A comb comprising a body strip, a series of straight teeth extending from said strip and a series of arcuate teeth extending downwardly from, laterally and upwardly of and inwardly toward said strip and having their free ends spaced from the upper edge of said strip to leave a predetermined gap therebetween, said arcuate teeth being of such length as to constitute the major portion of a circle.

4. A comb comprising a curved body strip, a series of straight teeth extending from said strip throughout its length, and a series of arcuate teeth extending from said strip throughout its length and substantially laterally of said series of straight teeth, the convex sides of said arcuate teeth being disposed toward the free ends of said straight teeth.

5. A comb comprising a curved body strip, a series of straight teeth extending from said strip throughout its length, and a series of arcuate teeth extending downwardly from, laterally and upwardly of and inwardly toward said strip throughout its length and having their free ends spaced from the upper edge of said strip to leave a predetermined gap therebetween.
